UNITED STATES PATENT OFFICE

107,439

DESIGN FOR AN AIR CONDITIONING APPARATUS

Fred C. McClellan, Oak Park, Ill.

Application September 28, 1937, Serial No. 71,852

Term of patent 3½ years

To all whom it may concern:

Be it known that I, Fred C. McClellan, a citizen of the United States and a resident of Oak Park, in the county of Cook and State of Illinois, have invented a new, original, and ornamental Design for an Air Conditioning Apparatus, of which the following is a specification, reference being had to the accompanying drawing forming a part thereof, and in which:

Fig. 1 is a perspective view of an air conditioning apparatus showing my new design;

Fig. 2 is an elevational view as seen from line 2—2 in Fig. 1;

Fig. 3 is an elevational view as seen from line 3—3 in Fig. 2; and

Fig. 4 is an elevational view as seen from line 4—4 in Fig. 3.

I claim:

The ornamental design for an air conditioning apparatus, as shown.

FRED C. McCLELLAN.
